PRESSURE-ACTUATED TUBING ANCHOR

Edward C. Brumleu and Walton E. Gilbert, Los Angeles, Calif.; said Gilbert assignor to Shell Development Company, San Francisco, Calif., a corporation of Delaware

Application October 30, 1943, Serial No. 508,364

11 Claims. (Cl. 103—219)

The present invention relates to improved apparatus for use in oil wells which are being produced by rod-actuated well pumps, and pertains more particularly to an apparatus for anchoring tubing or pipe strings in such wells. This application is a continuation-in-part of our application Serial No. 476,124, filed February 16, 1943.

It has long been recognized that the tubing through which a well is being pumped should be anchored near its lower end in addition to being supported at the top, since the cyclical change in fluid load due to the pumping action would otherwise result in an appreciable motion of the lower end of the tubing. Thus operators frequently resort to anchoring the tubing near its lower end in order to eliminate external wear of tubing joints and collars, and to improve pumping efficiency by preventing the partial loss of pump stroke which attends tubing motion.

In the past, this has been accomplished by setting the tubing on a device commonly known as a "tubing anchor," which is usually set by putting at least part of the tubing in compression. This conventional method of anchoring tubing has been unsatisfactory in that it depends upon the human element to judge the amount of compression in which the pipe is set. Also, the conventional method of setting anchors in compression very frequently results in severe wear of rods and internal wear of tubing by abrasive rubbing in the reverse curves of the section of the tubing under compression, which rubbing action promotes working of tubing joints and results in a concentration of leakage troubles in the compressed tubing section. Devices have likewise been made which would allow the anchoring of tubing in tension, but these devices have again depended on the human element in putting the correct amount of tension in the tubing.

Also, it is not practicable under the best circumstances to set the usual type of tubing anchor without an unnecessary extra length of tubing in compression. In practice, the usual type anchor is set in compression before the rods are installed in the well. Consequently the compression load on the anchor, and the corresponding length of tubing in compression above the anchor, are both materially increased when pumping starts and the tubing is filled with fluid to the surface. Actually, the differential load, which must be supported by the anchor to prevent deleterious reciprocating motion of the tubing, is only a fraction of the total fluid load, being that part of the latter approximately defined by the ratio of the pump-plunger area divided by the inside

area of the tubing. As a result, both the compression load imposed in setting the conventional anchor and the part of the fluid load steadily imposed on the anchor (which is approximately the total fluid load multiplied by one minus the ratio of the pump plunger area over the inside tubing area) represents extra compressive loading which is not needed to prevent motion of the lower end of the tubing but which is normally applied in setting conventional tubing anchors.

It is, therefore, an object of this invention to eliminate compressive loading entirely by running the tool in tension or, alternatively, by running the tool in compression so that it sets automatically and assumes only a predetermined part of the fluid load.

It is also an object of this invention to provide means of performing the useful functions priorly performed by conventional compression-type tubing anchors and at the same time to obviate the deleterious and harmful effects above mentioned which are consequent upon use of compression-type anchors of usual types.

It is also an object of this invention to provide an improved positively controlled tubing anchor adapted to be set in a well or removed therefrom by the application of fluid or hydraulic pressure without the necessity of rotating the tubing, thus eliminating the cause of many accidents incidental to use of tubing anchors in the past.

More specifically, it is an object of this invention to provide a tubing anchor which can be set in a well by actuating a gripping mechanism by means of the differential hydraulic pressure existing between the pressure head of the liquid column raised in the tubing by the pump, and the pressure head of the liquid standing in the well.

Another important object of this invention is to provide an improved tubing anchoring device, which, when used in tension, automatically adjusts its depth location in response to any increase in pumping loads or increase in the temperature of the tubing, and thus eliminates the human element in its setting, and which, when used in compression, is automatically set by hydraulic pressure without any need of length adjustment of the tubing at the well head, and effectively prevents tubing motion with considerably less length of tubing in compression than the minimum necessary in setting conventional types of anchors.

A still further object of this invention is to provide a device of the character described which is safe in operation, simple in construction, economical to build and operate, and which insures

reduction of physical depreciation of the tubing and rods and the maintenance of favorable pumpstroke efficiencies.

With the above and other objects and advantages in view, the invention has particular relation to the arrangement and construction of parts, an example of which is described in this specification and illustrated in the accompanying drawings, wherein:

Figure 1 is a view, partly in elevation and partly in section, of a preferred embodiment of the tubing anchor of the present invention.

Figure 2 is a cross-section taken along the line 2—2 of Figure 1.

Figure 3 is a cross-section taken along the line 3—3 of Figure 1.

Figures 4 and 5 give a diagrammatic view, partly in elevation and partly in section, of the tubing anchor in position in the bore of a well, together with other equipment pertinent thereto.

Briefly, the tubing anchor of the present invention is pressure-actuated and comprises a tubular mandrel connected into the tubing string as a part thereof, a slidable plunger sleeve surrounding the upper portion of said mandrel, said mandrel and piston sleeve defining a pressure chamber therebetween, a port or ports providing communication between the bore of said mandrel and said pressure chamber, resilient means tending to hold the piston sleeve at or near the upper limit of its travel, a taper element on said mandrel, well-gripping elements or slips adapted to be slidably supported from said sleeve and to be guided into an operative position in engagement with the well casing by said taper element, and resilient connecting means between said gripping means and said piston sleeve, whereby said gripping means are maintained in operative position even when the tubing string is subjected to an elongating stress.

The device may be used with the tubing anchored either in tension or compression. Since words like "upward" and "downward" are useful in describing the action and parts of such a device, and as a matter of maintaining clarity, the device is depicted and described as it is used with tension loading. The changes consequent upon using the device for compressive loading will be explained hereinbelow.

Referring to Figs. 1 to 3 of the drawings, the tubing anchor includes a tubular mandrel 10 having externally threaded end portions 11 and 12. A downwardly diverging tapered member 13 is fitted over the lower end of the tubular member 10 and is securely held in place against a projecting shoulder 14 on said mandrel 10 by a threaded collar 15. This collar 15 may be provided with a lateral port or ports 16 fitted with a closure disc or discs 17 held in place by means of a bushing 18 for a subsequently described purpose. The gripping elements or slips 20, having toothed or serrated faces 21, are held in slidable engagement with the tapered faces of the tapered member 13 by means of keys 22 on slips 20 and keyways 23 in tapered member 13. By-pass spaces 24 are provided on the tapered member 13 to allow maximum practicable cross-sectional areas for passage of fluid up the annular space.

Threadably attached to the upper threaded end portion 11 of the tubular mandrel 10 is a tubular member 30 of a slightly larger outside diameter than tubular mandrel 10. Tubular member 30 is provided with an external annular groove 31 adapted to receive a packing element or elements 32. The upper end 33 of the member 30 is thread-

ed with a left hand thread for connection to a substitute 34 which in turn is provided at its upper end with a threaded portion 35 for connection to a tubing string.

A tubular sleeve 40 has a thickened lower portion 41 fitting slidably about the mandrel 10, and an upper portion 42 of larger inside diameter fitting slidably about tubular member 30. The upward travel of sleeve 40 is limited by contact of portion 41 with enlarged tubular member 30. An internal annular groove 43 is provided in the thickened lower portion 41 of sleeve 40 and carries a sealing element or elements 44. By this arrangement, the tubular sleeve 40, mandrel 10 and tubular member 30 form a pressure chamber 46 therebetween. A port or ports 47 extends laterally through the mandrel 10 and provides fluid communications between the bore of mandrel 10 and the pressure chamber 46. Resilient means, preferably a coil spring 50, surrounding said mandrel 10 and acting at one end against the upper transverse face of the tapered member 13 and at the other end against the lower transverse face of the sleeve 40 tends to hold the sleeve 40 at or near the upper limit of its travel. With the application of fluid pressure through the lateral port 47 into the pressure chamber 46, the sleeve 40 acts as a piston and is forced downward compressing coil spring 50 as will subsequently be described. A fishing neck 51 may be provided on the upper end of the sleeve 40. Rotation of the sleeve is prevented by means of a key lug 52 on the tubular member 30 riding in a vertical key slot 53 in the sleeve 40.

The slips 20 are provided with upwardly-extending actuating arms 55 which are resiliently connected to the pressure-actuated sleeve 40 by suitable means. For example, in a preferred arrangement, the upper end of the slip actuating arms 55 is enlarged in a circumferential direction as at 56, as shown in Figures 1 and 2. The external part of the thickened lower portion 41 of the sleeve 40 is formed with a radially projecting annular portion 58 having vertical slots 59 radially deeper than the thickness of the slip arms 55 and having a relatively shallow annular groove 60 in the lower portion. The slots 59 are just wide enough to receive the slip arms 55, but too small to allow the circumferentially enlarged upper end 56 of said arms 55 to pass therethrough. The arms 55 are positioned in these annularly-spaced slots 59 with the enlarged ends 56 of the arms 55 resting on the upper transverse face 61 of the outwardly-projecting portion 58 of the sleeve 40. Also resting on said face 61 and surrounding the enlarged upper ends 56 of the slip arms 55 is a retaining ring 65. Sprung into place in the groove 60 is a split resilient metal retaining ring 66. Thus, the slip arms 55 are slidably connected for a limited vertical travel to the sleeve 40. Surmounting the upper ends 56 of the slip arms 55 and the upper retaining ring 65 and fitting slidably around the pressure-actuated sleeve 40 is a sleeve 70. Also, surrounding the pressure-actuated sleeve 40 and compressed between the sleeve 70 and a retaining nut 71 threadedly attached about the upper portion of the pressure-actuated sleeve 40 is a relatively light coil spring 72, which tends to hold the sleeve 70 and the slip arms 55 therebelow at the lower limit of their vertical travel. This connecting arrangement between the slip arms 55 and the pressure-actuated sleeve 40 provides means for automatically adjusting the force acting on the slip arms 55. Such adjusting means or resilient connec-

tion is necessary, since the sleeve 40 may be forced downward somewhat beyond the point at which the slips 20 fully engage the casing and since the slip arms 55 are preferably not designed to withstand large compressive loads.

In operation (see Figures 4 and 5), the tubing anchor is lowered into a well on the lower end of the tubing string 80. A tubing catcher 81 may be attached below the tubing anchor so as to provide means for catching the tubing string 80 in case it should be inadvertently dropped while lowering or raising. A pump 82 with its standing valve 83 and a travelling valve 84 is then lowered into the well on the lower end of a sucker rod string 85. Power is transmitted to the pump 82 through the reciprocating motion of the rod string 85, and the pump 82 raises well fluids to the surface. A packing gland 87 surrounds the rod string 85 at the well-head to prevent leakage of well fluids thereby. A flow line 88 is provided to conduct the well fluids to storage in the conventional manner. When the pump 82 is started, well fluids are pumped up into the tubing above the pump 82. Each successive pumping stroke of the pump 82 causes the well fluids to rise higher above the pump 82. When the fluid in the tubing has risen to a point where its differential fluid pressure over the annular area at the lower end of the pressure chamber 46 exceeds the compression in spring 50, the movable sleeve 40, slip arms 55 and slips 20 all move downward until the slips 20 engage the walls of the casing 90, as shown in Figure 4. After the slips 20 have engaged the casing 90, the pressure-actuated sleeve 40 continues to move downward to its lower position and the slip arms 55 acting in an upward direction against the sleeve 70 compress the relatively light spring 72. Thus, all the compressive load except that due to compression spring 72 is eliminated from slip arms 55. As the fluid head in the tubing 80 rises and the temperature of the tubing increases, the tubing will tend to elongate. However, the compression in spring 72 transmitted continuously against the slips 20 keeps them forced down and outward against the casing 90 at all times permitting the tubing anchor to adjust itself downward to an operative position in response to any elongation of the tubing 80.

When it is necessary to remove the tubing 80 from the well, the pump 82 and the standing valve 83 is unseated and removed from the well by lifting the rod string 85. This allows the fluid in the tubing 80 above the pump 82 to fall back down the tubing 80 and into the annular space 91 between the tubing 80 and the casing 90 until such time as the levels and fluid pressures in the tubing 80 and annular space 91 become equalized. This equalization of pressures removes the downward force held against the spring 50 so that the spring 50 moves the sleeve 40 upward until its outwardly projecting portion 58 contacts the radially enlarged upper ends 56 of the slip arms 55. Since the teeth 21 of slip 20 have bitten into the walls, it is then only necessary to lower the tubing 80 a few inches at the level of the tubing anchor, thus lowering the tapered member 13 and permitting radial contraction of the slips 20, whereby the tubing anchor is freed from its hold on the casing 90. The spring 50 is then free to force the sleeve 40 back to the upper limit of its travel with the slips 20 fully retracted radially.

To facilitate release of the tubing anchor, a special arrangement of surface connections at

the well-head such as shown in Figure 4 is preferred. The handling procedure at the well-head is as follows: The sucker rod packing gland 87 is removed, the pump 82, standing valve 83 and rod string 85 are withdrawn from the well, a conventional lifting nipple is then inserted and attached to the internal threads 93 at the upper end of the substitute 94 which connects the tubing 80 to the supporting flange 95. The flange bolts 96 are removed, allowing the flange 95 to be unscrewed from substitute 94 and to be lifted clear of its packing ring 87. By using a lifting nipple of appropriate length, the tubing 80 is then free to be lowered enough to provide a few inches (for example, 5 inches) of downward movement of the tubular mandrel 10 of the tubing anchor. This is sufficient to free the gripping engagement of the slips 20 on the casing 90 as previously described.

In case the pump 82 has become, for any reason, stuck or sanded to such an extent that it cannot be pulled loose so as to allow equalization of pressure in the tubing with that in the annular space 91, discs 17 (Figure 1), which are formed of a metal of predetermined bursting strength, can be blown out by the addition of excess pressure in the tubing 80 at the top of the well. The bursting of the discs 17 will allow the fluid pressures in tubing 80 and in the annular space 91 to equalize, thereby allowing the tubing anchor to be released by a short downward movement of the tubing 80 and the tubular mandrel 10. If under extraordinary circumstances both of these procedures for release of the tubing anchor should prove ineffective, right hand rotation of the tubing 80 will cause the unscrewing of the left hand thread 33 which connects the substitute 34 to the upper tubular member 30. The tubing 80 may then be removed and a suitable fishing tool run in to grip the fishing neck 51, whereby removal of the tubing anchor and appended tubing is insured.

It will be seen that the tubing anchor of the present invention is simple in structure and operation and eliminates complicated operations in setting the tubing anchor at the proper position in the well. There is no need for rotating the tubing 80 in the ordinary procedure for setting or releasing the present tubing anchor. Thus an operation which has proven hazardous in the setting and releasing of tubing anchors is eliminated. Since the tubing anchor of the present invention automatically adjusts itself to the varying conditions existing in each individual well, there can be no error in the amount of tension carried in the tubing string 80.

It is desired to make particular mention of the fact that the device may be run with tubing in compression rather than in tension, as above described. When used in this alternative manner, the anchor is connected in a position upside down to that described. It may be released by collapse of the hydraulic pressure or may be pulled out of the hole without releasing, if necessary, because the spring 72 is light enough to permit relative motion between slips 20 and conical member 13 without injuring slip arms 55. Further, when run in this manner, the fishing neck 51, the discs 17, and the left-hand thread 33 may be, if desired, eliminated as unnecessary. Also, when the tool is run in compression, no special arrangement of surface connections, such as shown in Fig. 4, is necessary.

Although the present invention has been described in relation to a particular embodiment

thereof, it will be readily apparent that various modifications and changes can be made in the structure of the present tubing anchor without departing from the scope of the invention as defined by the appended claims.

We claim as our invention:

1. In a well-pumping installation for a cased well, a string of tubing, a pump at the lower end thereof for raising a column of liquid in said tubing, a plunger sleeve surrounding said tubing above the pump, said tubing and sleeve defining therebetween a pressure chamber, port means in said tubing, whereby said plunger sleeve is moved by applying thereto the hydrostatic pressure of the liquid raised by the pump within the tubing, spring means adapted to oppose said motion, gripping means attached to said sleeve, a taper element carried by said tubing, said gripping means being adapted to be guided by said taper element into engagement with the well casing upon a pressure-responsive motion of said sleeve, and out of engagement therewith upon a spring-responsive motion of said sleeve.

2. In a well-pumping installation for a cased well, a string of tubing, a pump at the lower end thereof for raising a column of liquid in said tubing, a plunger sleeve slidably surrounding said tubing above said pump, spring means adapted to urge said plunger sleeve in one axial direction, means comprising lateral ports in said tubing for moving said plunger sleeve in the opposite axial direction against the action of said spring by applying thereto the hydrostatic pressure of the liquid raised by the pump within the tubing, gripping means attached to said sleeve, a taper element carried by said tubing, said gripping means being adapted to be guided by said taper element into engagement with the well casing upon a motion of said sleeve in said second direction, and out of engagement therewith upon a motion of said sleeve in said first direction.

3. In a well-pumping installation for a cased well, a string of tubing, a pump at the lower end thereof for raising a column of liquid in said tubing, a plunger sleeve slidably surrounding said tubing above said pump, spring means adapted to urge said plunger sleeve in one axial direction, means comprising lateral ports in said tubing for moving said plunger sleeve in the opposite axial direction against the action of said spring by applying thereto the hydrostatic pressure of the liquid raised by the pump within the tubing, gripping means slidably supported by said sleeve, a taper element carried by said tubing, said gripping means being guided by said taper element into engagement with the well casing upon a pressure-responsive motion of said sleeve, and second spring means adapted to move said gripping means with regard to said sleeve in the direction of the pressure-responsive motion of said sleeve.

4. In a well-pumping installation for a cased well, a string of tubing, a pump at the lower end thereof for raising a column of liquid in said tubing, a plunger sleeve slidably surrounding said tubing above said pump, an annular pressure chamber defined between the tubing and said sleeve, spring means adapted to urge said plunger sleeve in one axial direction, means comprising ports between the inside of the tubing and said chamber for moving said plunger sleeve in the opposite axial direction against the action of said spring by applying the hydrostatic pressure of the liquid raised by the pump within the tubing to said chamber, gripping means attached to

said sleeve, a taper element carried by said tubing, said gripping means being adapted to be guided by said taper element into engagement with the well casing upon a pressure-responsive motion of said sleeve, and out of engagement therewith upon a spring-responsive motion of said sleeve.

5. In a well-pumping installation for a cased well, a string of tubing, a pump at the lower end thereof for raising a column of liquid in said tubing, a plunger sleeve slidably surrounding said tubing above said pump, an annular pressure chamber defined between the tubing and said sleeve, spring means adapted to urge said plunger sleeve in one axial direction, means comprising ports between the inside of the tubing and said chamber for moving said plunger sleeve in the opposite axial direction against the action of said spring by applying the hydrostatic pressure of the liquid raised by the pump within the tubing to said chamber, gripping means slidably supported by said sleeve, a taper element carried by said tubing, said gripping means being guided by said taper element into engagement with the well casing upon a pressure-responsive motion of said sleeve, and second spring means adapted to move said gripping means with regard to said sleeve in the direction of the pressure-responsive motion of said sleeve.

6. In a well-pumping installation comprising a cased well and a pump lowered thereinto at the end of a tubing string, an anchor for said tubing, said anchor comprising a tubular mandrel adapted to be connected into said tubing string above the pump, a plunger sleeve slidably surrounding said mandrel, an annular pressure chamber defined between said mandrel and said sleeve, means comprising lateral ports in said mandrel in communication between the inside of the string and said chamber for moving said plunger sleeve by applying the hydrostatic pressure of the liquid raised by the pump to said chamber, spring means adapted to oppose said motion, gripping means attached to said sleeve, and a taper element attached to said mandrel, said taper element being adapted to guide said gripping means into engagement with the well casing upon a pressure-responsive motion of said sleeve, and out of engagement therewith upon a spring-responsive motion of said sleeve.

7. In a well-pumping installation comprising a cased well and a pump lowered thereinto at the end of a tubing string, an anchor for said tubing, said anchor comprising a tubular mandrel member adapted to be connected into said tubing string above the pump, a plunger sleeve slidably surrounding said mandrel, an annular pressure chamber defined between said mandrel and said sleeve, spring means adapted to urge said sleeve in one axial direction, means comprising ports in said mandrel in communication between the inside of the string and said chamber for moving said plunger sleeve in the opposite axial direction against the action of said spring by applying the hydrostatic pressure of the liquid raised by the pump to said chamber, gripping means slidably attached to said sleeve, a taper element attached to said mandrel, said taper element being adapted to guide said gripping means into engagement with the well casing upon a pressure-responsive motion of said sleeve, and second spring means adapted to move said gripping means with regard to said sleeve in the direction of the pressure-responsive motion of said sleeve.

8. A pressure-actuated tubing anchor compris-

ing a tubular mandrel adapted to be connected into a tubing string, a plunger sleeve member slidably surrounding said mandrel, an annular pressure chamber defined between said mandrel and said plunger sleeve, spring means urging said plunger sleeve in one axial direction, means comprising ports in communication between the inside of said tubular mandrel and said chamber for moving said plunger sleeve in the opposite axial direction against the action of said spring by applying to said chamber the fluid pressure within said mandrel, gripping means slidably attached to said sleeve, a taper element carried by said mandrel, said gripping means being adapted to be guided by said taper element into an operative position upon pressure-responsive motion of said sleeve and into an inoperative position upon a spring-responsive motion of said sleeve.

9. A pressure-actuated tubing anchor comprising a tubular mandrel adapted to be connected into a tubing string, a plunger sleeve member slidably surrounding said mandrel, an annular pressure chamber defined between said mandrel and said plunger sleeve, spring means urging said plunger sleeve in one axial direction, means comprising ports in communication between the inside of said tubular mandrel and said chamber for moving said plunger sleeve in the opposite axial direction against the action of said spring by applying to said chamber the fluid pressure within said mandrel, gripping means slidably attached to said sleeve, a taper element carried by said mandrel said gripping means being adapted to be guided by said taper element into

an operative position upon a pressure-responsive motion of said sleeve and into an inoperative position upon a spring-responsive motion of said sleeve, and second spring means adapted to move said gripping means with regard to said plunger sleeve, in the direction of the pressure-responsive motion of said sleeve.

10. In the apparatus of claim 6, second lateral port means in said mandrel in communication between the inside of said string and the well, and a frangible closure element for said port means adapted to be broken by the application of excess fluid pressure to the tubing string from the surface, whereby the liquid column within the tubing is drained into the well through said second port means, and the hydrostatic pressures within and without the tubing are equalized.

11. A pressure-actuated tubing anchor comprising a tubular mandrel, a slideable sleeve piston surrounding said mandrel at one end thereof, said mandrel and sleeve piston defining a pressure chamber therebetween, ports in communication between the bore of said mandrel and said pressure chamber, resilient means tending to hold said mandrel and sleeve piston in a position whereat the chamber defined therebetween has a minimum volume, a downwardly-diverging taper on the lower end of said mandrel, gripping elements adapted to move slidably on said taper, actuating arms attached to said gripping elements, and resilient connecting means between said actuating arms and said sleeve piston.
